UNITED STATES PATENT OFFICE.

THEODORE WIEDEMANN, OF PHILADELPHIA, PENNSYLVANIA.

TELESCOPIC MICROMETER-GAGE.

SPECIFICATION forming part of Letters Patent No. 686,497, dated November 12, 1901.

Application filed December 15, 1900. Serial No. 39,972. (No model.)

To all whom it may concern:

Be it known that I, THEODORE WIEDEMANN, a citizen of the United States, residing in the city and county of Philadelphia, State of Pennsylvania, have invented a new and useful Improvement in Telescopic Micrometer-Gages, of which the following is a specification.

My invention consists of an improved construction of a telescopic micrometer-gage which can be cheaply manufactured and is not liable to get out of order and which can be put to the same variety of uses as more expensive instruments of this character.

15 The invention also consists of novel means whereby the same can be readily utilized for measuring interior diameters of varying area according to requirements.

It also consists of novel details of construction, all as will be hereinafter fully described, and particularly pointed out in the claims.

Figure 1 represents a side elevation of a telescopic micrometer-gage embodying my invention. Fig. 2 represents a longitudinal sectional view of Fig. 1. Fig. 3 represents a longitudinal sectional view of a portion of the gage similar to the parts seen in Fig. 2, but viewed at a different angle. Fig. 4 represents an end elevation of a portion of the gage to be hereininafter referred to. Fig. 5 represents a side elevation of a portion of the gage, showing the scale thereon. Fig. 6 represents a side elevation, partly in section, showing the points seen in Figs. 1 and 2 removed and a 35 shell containing an extension of wood or other material inserted in position.

Similar numerals of reference indicate corresponding parts in the figures.

Referring to the drawings, 1 designates the 40 gage, the same consisting of the main tube 2, which has one end threaded and adapted to engage the threaded plug 3, which latter is provided with the flange or shoulder 4, which abuts against the extremity of the tube 2, 45 said plug also having the extension 5, upon which flange and extension is fitted the shell 6, having the point or contact part 7 in threaded engagement therewith. The shell 6 is forced tightly over the contiguous parts of 50 the threaded plug 3, thereby forming a solid screw-shell, said shell fitting neatly over the exterior of the tube 2 and having one extrem-

ity 8 beveled and provided with a scale 9, which is divided in the present instance into twenty-five (25) equal parts, which therefore 55 designate the thousandth part of one inch, it being understood that the opposite threaded portion of the shell 6, which is tapped to receive the point 7, can receive other points of any suitable character, whereby I can make 60 up any desired length.

10 designates a screw provided with a tapered head 11, which is nicely fitted into the threaded plug 3, which latter is split at 3^X for a portion of its whole length, in the present 65 instance about two-thirds, ($\frac{2}{3}$), whereby ample provision is made to take up any possible wear between the threaded plug 3 and the threaded end of the tube 2. The end of the tube 2 opposite to the threaded plug 3^X is provided with a tapered nut 12, whereby the tube 13, which telescopes within the tube 2, can be held in any desired position. On the outer extremity of the telescopic tube 13 is located the nut 14, substantially similar in construction 75 to the nut 12, said nut 14 serving to hold in the desired position the rod or contact part 15.

16 designates a sleeve which is fitted over the tube 2 and is connected by the pin 17 to the tube 13, whereby said tube 13 and the sleeve 80 16 always move in unison inside as well as outside of the tube 2, which has the slots 18 therein, through which said pin 17 passes. The beveled end 19 of the sleeve 16 works as an indicator upon a scale 20 on the tube 2, 85 which is graduated to thirty-seconds of an inch.

21 designates a spiral tension device that consists of a spring which has one end thereof contacting with the pin 17, while the other 90 end of said spring abuts against the plunger 22, which is provided with the stem 23, which causes the spring 21 to be retained at all times in proper position relative to said plunger, the latter resting against the contiguous 95 shoulder or extremity of the threaded plug 3, as will be understood from Fig. 2.

When it is desired to lengthen the gage, I remove the threaded point 7 and insert therein the threaded stem 24 of the threaded 100 shell 25, into which latter is inserted the extension 26, whereby the gage can be lengthened to any desired extent, as is evident.

It will be apparent from the foregoing that

- by means of the micrometer any size can be taken in thousandths of an inch, while the telescopic arrangement of the parts allows the gage to be set to two sizes within the limits 5 of approximately one inch, the larger size to be taken by means of the extension-points and the smaller by means of the telescopic tubes 2 and 13 and the graduations 20 on said tube 2, and it will be further apparent that 10 by tightening the two nuts 12 and 14 on the ends of the tubes the device can be readily used as a solid gage.

It is understood, of course, that by means of the split end of the tube 13 and the nut 14 the rod 15 can be adjusted so as to increase 15 or diminish the length of the instrument and that by means of the nut 12 the tube 13 can be held in any adjusted position. For instance, after a certain measurement has been 20 taken this nut 12 can be tightened up, so as to retain the parts in such position. In using this micrometer, for instance, for measuring the inside diameter of a pipe or other tubular object the tube 13 is telescoped within the 25 tube 2 against the tension of the spring and placed within the pipe or other object and then released. The tension device or spring 21 will force the tube 13 downwardly until the rod or contact-point 15 and the point or 30 contact part 7 engage opposite sides of the pipe. The measurement can then be read upon the gage 20 on tube 2, or the nut 12 can be tightened and the micrometer removed. The shell 6, which is used to indicate 35 in the present instance variations amounting only to one-thousandth part of an inch, by being rotated is moved longitudinally relative to the tube 2, the graduations 9 on said sleeve indicating such measurement in connection with any suitable fixed point on the 40 tube 2.

Having thus described my invention, what I claim as new, and desire to secure by Letters Patent, is—

45 1. In a micrometer-gage, the combination of a main tube, an inner tube telescoping therein, a shell rotatably movable on said main tube, a series of graduations on said main tube, a sleeve longitudinally movable 50 on the latter, and contact parts carried by the extremities of said gage.

2. In a micrometer-gage, a main tube having a threaded plug in engagement therewith, a shell mounted on said plug and main tube, 55 a sleeve carried by the latter, an inner tube telescoping within said main tube, a pin common to said sleeve and inner tube, said pin being movable in slots in said main tube, a plunger located within said main tube, and a 60 spring intermediate said pin and plunger.

3. In a micrometer-gage, a main tube having a threaded plug in engagement therewith,

a shell mounted on said plug and main tube, a sleeve carried by the latter, an inner tube telescoping within said main tube, a pin common to said sleeve and inner tube, said pin being movable in slots in said main tube, a plunger located within said main tube, and a spring intermediate said pin and plunger, in combination with a rod telescopically mounted 65 within said inner tube. 70

4. In a micrometer-gage, a main tube having a threaded plug in engagement therewith, said plug being split for a portion of its length, a screw seated in said plug and having a tapered head, a shell mounted on said plug and main tube, a series of graduations on the latter, a sleeve longitudinally movable on said main tube, and contact parts carried by the extremities of said gage. 75 80

5. In a micrometer-gage, a main tube, a threaded plug in engagement with one end thereof, said plug being split for a portion of its length and having a threaded screw in engagement therewith, a flange on said plug and adapted to contact with the end of said main tube, a shell mounted on said main tube and plug, a sleeve mounted on said main tube, an inner tube telescoping within said main tube, a rod telescoping within said inner tube, and nuts mounted upon said inner tube and main tube. 85 90

6. In a micrometer-gage, a main tube having a scale thereon, a sleeve mounted on said main tube, an inner tube telescoping within said main tube, a rod telescoping within said inner tube, and a tension device common to said main tube and inner tube. 95

7. In a micrometer-gage, a main tube having a split plug in engagement with one end thereof, a screw having a tapered head seated in said plug, a shell mounted on said plug and main tube and provided with graduations, a sleeve mounted on said main tube, the latter having a scale thereon, an inner 100 tube telescoping within said main tube, a rod adjustably mounted in said inner tube, nuts 105 for holding said inner tube and rod in any desired position, a pin common to said sleeve and inner tube, a plunger located within said inner tube, and a spring intermediate said plunger and pin. 110

8. In a micrometer-gage, a main tube, an inner tube telescopically mounted therein, a shell mounted on said main tube and interiorly threaded for the reception of an extension, an adjustable rod mounted in the opposite extremity of said gage, and means for securing said rod in adjusted position. 115
